UNITED STATES PATENT OFFICE.

FRANK J. SPRAGUE, OF NEW YORK, N. Y., ASSIGNOR TO SAMUEL INSULL,
TRUSTEE.

ADJUSTABLE RESISTANCE FOR ELECTRICAL CIRCUITS.

SPECIFICATION forming part of Letters Patent No. 309,167, dated December 9, 1884.

Application filed April 2, 1884. (No model.)

To all whom it may concern:

Be it known that I, FRANK J. SPRAGUE, of New York, in the county and State of New York, have invented a certain new and useful Improvement in Adjustable Resistances for Electrical Circuits, of which the following is a specification.

The object of my invention is to provide an adjustable resistance of compact and convenient form, in which there shall be very little metal not in use at any time, variations of resistance being produced by the different combinations into which a small number of coils are thrown by the movement of the adjusting devices.

My invention consists in the novel devices and combinations of devices employed by me in accomplishing the above-named object, as will be hereinafter specified.

20 The invention is illustrated in the accompanying drawings, in which Figure 1 is a side view of the resistance-box with the switch-boards in section; Fig. 2, a front elevation of the same; Fig. 3, a larger vertical section of 25 one of the resistance-controlling arms; Fig. 4, a diagram of the switch-boards, resistance-coils, and connections; and Fig. 5 a top view of the resistance-coils with the connections in diagram.

30 My invention is not confined, of course, to the exact number and arrangement of resistance-coils and contact-plates shown and described. These are, however, such as I have found convenient in practice.

35 A is a wooden frame or box, in which are supported, preferably in a vertical position, twenty-four coils, B, of iron or other wire, of such conducting capacity as may be desired for the particular situation in which the apparatus is to be placed.

40 Upon the top of the box or frame A are two wooden switch-boards, C and C', united by the cross-pieces D D.

Upon switch-board C are contacts *a a'*, &c. 45 Upon board C' are contacts *b b'*, &c. These contacts are forked metal pieces, the contact being made by forcing a metal plate between the forked portions. The contact-arms—one for each switch-board—are carried by the 50 shaft or spindle E, which passes through the two boards. Only one of these arms is shown

in Fig. 1, and, as they are exactly alike I will describe one of them. An insulating-sleeve, *c*, is placed upon the shaft, such sleeve being split, as shown. The sleeve is clamped upon 55 the shaft by the metal sleeve *d*, which is secured by nut *e*. In one direction from sleeve *d* extends the arm *f*, which carries contact-plate *g*, this being adapted to enter between the forked portions of the contacts *a* or *b* upon 60 the switch-board, fitting therein so as to make a good electrical connection. Opposite the arm *f* the split and forked metal piece *h* extends from sleeve *d*. All these connected metal parts may be made in one piece, if de- 65 sired. A metal ring, *k*, is supported upon each switch-board by pins *l l*, and the metal piece *h* makes contact with this ring, as shown, by clasping the ring between its two parts. It will be seen that as the shaft E is turned 70 the pieces *d* are constantly in contact with rings *k*, while the connections of plates *g* with contacts *a* and *b* are changed as desired.

The circuit-connections are as follows: Four large conductors, *m m' m'' m'''*, extend along the 75 bottom of the supporting box or frame between the coils, and each is brought up vertically at one end and connected to one of the contact-plates, *a* or *b*. In Fig. 1 this connection is not shown, the conductors being broken 80 off above the supporting-frame. The other ends of these conductors are free. The lower ends of the resistance-coils are separately connected to the conductors *m m'*, &c. The upper ends of the coils are connected to wires 85 *o o' o'' o''' o''''*, which extend along under the top of the frame A, and which are connected with the circuit, as will be presently explained. The coils are connected to these conductors *o* in sets of three each, so that three coils are 90 in multiple arc to one another. Thus three multiple-arc coils form the unit of the resistance, the resistance being varied by changing the number and relation of such units.

One or two or any number of coils might be 95 separately connected between conductors *o* and *m* to form the unitary resistance; but I have chosen three as a convenient number.

Now, referring to Fig. 4, the sections of coils marked *pp' &c.*, each represents one of the units 100 of resistance—three coils in multiple arc, or such other number in such arrangement as may

be selected. The switch-boards are, for the purpose of illustration, laid out side by side. The arrows on the switch-boards show the direction of revolution of the contact-arms. Each 5 switch-board is, for convenience of explanation, shown as divided into thirty-eight equal parts upon its circumference.

M M is the conductor of the circuit whose resistance is to be varied. It is broken and 10 connected through rods q q with the rings h h of the switch-boards. Connection o from the tops of the resistance-coils extends direct to the conductor M; o' extends to contacts a² and b², o² to contacts a' and b', o³ to contacts a³ and b³, and o⁴ to contacts a and b. Connections m, 15 m', m², and m³ from lower ends of coils extend, respectively, to contacts b¹, b², b³, and b⁴. Arrows r indicating direction of current in the position of the contact-arms shown, the resistance-units are in circuit all in series, there being, as is readily seen, no passage for the current from one part of the conductor to the other, except by o, all the coils p o', and q, h, k, and q upon switch-board C'. Now, if it 20 is desired to cut out resistance from the circuit, by turning wheel W the contact-arms are moved in directions indicated by the arrows. A movement of one of the thirty-eight divisions brings the right-hand arm upon contact 25 b' without changing the connection of the other arm. All the coils on the right of o² will then be short-circuited and the resistance halved. The next change is produced by moving six divisions, which brings the left-hand arm 30 upon contact a, and right-hand arm off of b. This divides the resistance into two halves, coils p, p', p², and p³ being multiple-arc'd upon p¹, p⁵, p⁶, and p⁷. It is unnecessary to follow out all the movements in detail. The coils 35 are brought through different combinations of multiple arc and series, or are cut out of circuit as occasion requires. At the termination of the movement the left-hand arm is upon a², a³, a', and a⁵ and the right upon b⁴ and b⁵. The resistance is thus entirely short-circuited. 40 By this arrangement of contacts the greatest changes of resistance occur when a large resistance is in circuit, and the extent of the changes becomes less as the whole resistance

in circuit becomes less. It is thus well adapted for use with the feeding-circuits of electrical-distribution systems, the greatest resistance being in circuit when only a few lights are on, and when the addition of one or two lights makes a great change in the whole 55 resistance of the circuit. The division of the contacts between two switch-boards, with the resistance-coils connected between them, makes the apparatus much more compact, as a very large switch-board would be necessary 60 if all the contacts were placed upon one.

What I claim is—

1. In an adjustable resistance, the combination of two series of metallic contacts, resistance-coils connected between them, and a circuit-controlling arm for each series, substantially as set forth. 65

2. The combination of the two switch-boards, each having a circular series of contacts, the resistance-coils connected between them, the 70 revolving contact-arms—one for each switch-board—and the common shaft for revolving them, substantially as set forth.

3. The combination of the two switch-boards, each having a series of contacts, the resistance-coils connected between them, and a connection from one end of the series of coils direct to the circuit, whereby all the coils may be placed directly in circuit, substantially as set forth. 75

4. The combination of the two switch-boards, each having a series of contacts, the resistance-coils connected between them, and a connection between them independent of the coils, whereby said coils may be short-circuited, substantially as set forth. 80

5. The combination of the box or frame supporting the resistance-coils, the two switch-boards placed back to back upon said frame, and the shaft passing through both switch-boards and carrying a contact-arm for each, substantially as set forth. 85

This specification signed and witnessed this 19th day of March, 1884.

FRANK J. SPRAGUE.
